United States Patent Office

Des. 219,915
Patented Feb. 16, 1971

219,915

PREFABRICATED FIREPLACE

Edwin L. McElheny, R.R. 1, Nappanee, Ind. 46550

Filed Jan. 15, 1970, Ser. No. 20,938

Term of patent 14 years

Int. Cl. D23—03

U.S. Cl. D23—97

FIG. 1

FIG. 3

FIG. 2

FIG. 1 is a perspective view of a prefabricated fireplace embodying the present design;

FIG. 2 is a front elevational view thereof on a reduced scale, the screen mesh being fragmentarily shown for convenience of illustration; and

FIG. 3 is a side elevational view thereof on a reduced scale.

The flue is broken away in FIGS. 1, 2, and 3 to indicate indeterminate length.

I claim:

The ornamental design for the prefabricated fireplace, as shown and described.
